UNITED STATES PATENT OFFICE.

FRANCIS T. JOHNSON, OF CHICAGO, ILLINOIS.

IRONING-BOARD.

1,133,145.

Specification of Letters Patent. Patented Mar. 23, 1915.

Application filed May 8, 1914. Serial No. 837,104.

To all whom it may concern:

Be it known that I, FRANCIS T. JOHNSON, a citizen of the United States, residing at Chicago, in the county of Cook and State 5 of Illinois, have invented a certain new and useful Improvement in Ironing-Boards, of which the following is a specification.

My invention relates to improvements in ironing boards and is illustrated in one form 10 in the accompanying drawing, wherein—

Figure 1 is a side elevation; Fig. 2 is a back plan view; Fig. 3 is a cross section on the line 3—3 of Fig. 1; Fig. 4 is a similar section on an enlarged scale.

15 Like parts are indicated by like letters throughout the several figures.

A is a conventional form of ironing board larger at one end than at the other and rounded at one end.

20 A¹, A¹ are supporting legs therefor braced by the braces A².

B, B are supporting clamps attached at their central portions to the ironing board as indicated and projecting toward the outer 25 edges of the board. The spring clamps which, as at B¹, are centrally engaged with the bottom side of the board, have at either end portions B² inclined to the body of the spring clamp B, but arranged for substantial 30 parallelism with the bottom of the board when in operating position.

B³, B⁴ are clamping blocks or bars adapted to engage the bottom of the board A and to be held in position by the springs B resting upon the flat surfaces B². The clamping bar B³ is provided with curved extension B⁵ adapted to underlie the smaller end of the board and be concentric with the curved part thereof.

35 B⁶ is a spring extension projecting across the rear end of the board and attached to and carried by the clamping bar B⁴.

C is a cover cloth adapted to overlie the board and extend around and under it and 40 to be held in position as indicated in Figs. 1 and 4 by the clamping bars B³, B⁴ and extensions B⁵, B⁶.

It will be evident that while I have shown 45 in my drawings an operative device, still many changes might be made both in size, shape and arrangement of parts without departing materially from the spirit of my invention, and I wish, therefore, that my

drawings be regarded as in a sense diagrammatic.

The use and operation of my invention are as follows: The cover cloth or sheet is spread over the board in the usual manner, being allowed to hang down around it on all sides. The clamping bar which has the 55 curved extension is then brought down to engage a portion of the sheet and is brought up against the under side of the board and moved inwardly and rearwardly until it is engaged by the clamps, the sheet being thus 60 held frictionally between the bar or spring extension and the board. The other clamping bar is then brought into position in the same manner until it assumes the position 65 shown in Fig. 2. By this means the sheet is 70 held tight to the board at all points without mutilation of the sheet and it may be easily detached at will by merely withdrawing the clamp bars from beneath the clamping springs.

75 I claim:

1. The combination of an ironing board and cover therefor of frictional means for yieldingly holding the cover in fixed position upon the board, said means being applied to said cover and board beneath the board and immediately inside the edge thereof, said means being substantially continuous about the periphery of the board and comprising a plurality of separate clamping 80 bars and yielding means for compressing 85 said bars against the board.

2. The combination of an ironing board and cover therefor of frictional means for yieldingly holding the cover in fixed position upon the board, said means being applied to said cover and board beneath the board and immediately inside the edge thereof, said means being substantially continuous about the periphery of the board and 90 comprising a plurality of separate clamping bars and yielding means for compressing 95 said bars against the board, said yielding means taking the form of spring clamps attached to the board which underlie the 100 clamping boards.

3. The combination of an ironing board and cover therefor of movable means for yieldingly holding the cover in fixed position upon the board, said means being applied to said cover and board beneath the 105

board and immediately inside the edge thereof, said means being substantially continuous about the periphery of the board and comprising a plurality of separate clamping bars and yielding means for compressing said bars against the board, said clamping bars having yielding extensions each at one end extending across the end of the board when the clamping members are in position,

one of said extensions being curved to correspond with the end of the board. 10

In testimony whereof, I affix my signature in the presence of two witnesses this 5th day of May 1914.

FRANCIS T. JOHNSON.
